UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A SPEEDOMETER DIAL.

Application filed February 6, 1924. Serial No. 8,544. Term of patent 7 years.

To all whom it may concern:

Be it known that I, JOHN K. OLSEN, a citizen of the United States, residing in the city of Chicago, in the county of Cook and the State of Illinois, have invented a new, original, and ornamental Design for a Speedometer Dial, of which the following is a specification, reference being had to the accompanying drawings, forming a part thereof.

The drawing is a face view of a speedometer dial embodying my new design.

I claim:

The ornamental design for a speedometer dial substantially as shown.

JOHN K. OLSEN.
